INVENTOR

Robert S. Hiltner

UNITED STATES PATENT OFFICE.

ROBERT S. HILTNER, OF LINCOLN, NEBRASKA.

CAN OR BOX OPENER.

No. 863,393.

Specification of Letters Patent.

Patented Aug. 13, 1907.

Application filed January 3, 1905. Serial No. 239,417.

To all whom it may concern:

Be it known that I, ROBERT S. HILTNER, a citizen of the United States, and residing in Lincoln, Nebraska, have invented certain new and useful Improvements in 5 Can or Box Openers, of which the following is a description, the accompanying drawings forming a part thereof.

An object of this invention is to provide a can or box opener which will be attached to the body of the can or box and therefore may not be lost or misplaced.

10 Another object of the invention is to provide a can opener which may be applied to the outside of the can body and will not therefore interfere with the contents of the same.

15 Another object of the invention is to provide a can opener which by being pivoted to the can body may be easily operated about its pivot and needs no other fulcrum point.

Still another object of the invention is to provide a can opener cheap to manufacture and easy and perfect 20 in operation.

Other objects of the invention will appear during the course of the specification.

Referring to the drawings on which like reference 25 letters represent like parts:—Figure 1 is a front elevation of the preferred form of opener applied to a round can. Fig. 2 is a plan view of the same. Fig. 3 is a vertical sectional view on line $s-s$ of Fig. 1. Fig. 4 is an elevation and plan of the preferred form of can opener, detached.

30 Fig. 5 is a modification of the can opener, detached. Fig. 6 is a vertical sectional view of the can opener, detached, showing a modification as to the rivet which attaches the same to the can.

Fig. 7 is a perspective view showing the can opener acting on the can cover. Fig. 8 is a vertical cross-section 35 taken through the rivet that holds the can opener in place on the can in Fig. 7, showing a modification in form and mode of attaching the opener. Fig. 9 is an elevation of a rectangular can or box having a modified form of can opener attached thereto. Fig. 10 is a

40 plan of the same. Fig. 11 is a cross section on the line $s'-s'$ of Fig. 9. Fig. 12 is a detail of the modified form of can opener shown in Fig. 9. Fig. 13 is a perspective view of the can opener of Fig. 9 operating upon the can cover.

45 In Figs. 1, 2, 3, 7, and 8, the letters A, B, and C designate respectively the top or cover, body, and opener of the can or box. The top or cover of the can is of ordinary construction, while the can body is changed only in countersinking the metal inward, as 50 at D, just around a hole a made in the same near the top rim. This countersinking is not absolutely necessary as will be seen by inspection of Figs. 7 and 8.

The can opener is a piece of sheet metal, formed as shown in Fig. 4, with a part b of suitable form, usually

circular or semi-circular, and having a hole a^3 in the same, and a part c bent at a right angle or other suitable angle to part b and forming shoulders d, d, where the two parts join. The part b is small enough to fit into the countersink D, and the part c is large enough to be easily grasped by thumb and fingers. The can opener 60 may be united to the can body by a rivet passing through the holes a and a^3 , or the rounded spur of metal at the back of b may be struck up as at a' , Fig. 6, and after the can opener has been put in place, the part a' may be beaded over. These parts are held together 65 loosely enough to allow the opener to swing freely about its pivot. In Fig. 5 a handle c^2 , shaped to conform to the shape of the box, is shown.

In the construction just described, the can opener does not interfere with the tight fitting of the cover on 70 the can body and moreover the can opener is securely fastened to the can.

By inspection of Fig. 7, the operation of the can opener is apparent. The handle c is grasped between the thumb and fingers. The opener, turning about the 75 pivot a, bears on one of the shoulders d against the under edge of the top or cover A and raises the same no matter how tightly the cover and box are fitted together.

In Figs. 9, 10, 11, 12, and 13 a slight modification is shown which is especially adapted for rectangular or 80 straight-sided boxes or cans without any heading on the same. The construction of the can or box is as usual. It is necessary only to punch a hole near the top of the body of the box or can just below the line of the lower edge of the cover. The can opener is formed of a flat 85 piece of sheet metal, cut as shown in Fig. 12, having a projection or nub a^2 and shoulders d^2 on one side. The nub is inserted into the hole in the can and headed over, as described in connection with the construction of Fig. 6. The operation of this form of can opener 90 is mechanically the same as in form shown in Figs. 1, 2, 7, and 8; the shoulders d^2 bearing against the under edge of the box cover as shown in Fig. 13 and raising the same by turning about the pivot a^2 .

The can openers herein described are especially 95 adapted to be applied to boxes for polishing pastes, ointments, etc. However they may be used on any can or box of whatever size or shape whose cover or top slips over, or wedges over, or telescopes over the can body. The construction herein set forth is capable of 100 many modifications without departing in the least from the spirit of the invention, and therefore I do not wish to be limited to the specific forms of can openers just described.

From the foregoing, it will be seen that my improved 105 lever opener for cans and boxes is unique in that it is permanently attached by rivet or other appropriate pivotal manner to the exterior of the body between the

flange of same and the cover. Being fastened to the can or box body it is always in place ready for use, and cannot be lost or mislaid.

Another novel feature of the device is that increased power in the lever is secured by attaching the opener to the can or box body at a point between the upper rim of said body and the lower rim of the over-lapping cover, thereby reducing to a minimum the length of the weight arm and thus increasing the efficiency of 10 the lever.

Still another novel feature of the invention is that all the members of the lever are on the outside of the can body: hence in operating the opener, the cover may be raised without disturbing the contents of the can 15 or box.

What I claim is:—

1. The combination of a can body, a cover, and a device pivotally attached to the body at a point in the outside of the body below the upper edge thereof and on that part 20 of the body which is over-lapped by the cover when in position and formed with a shoulder on both sides of the pivot point: said device being so arranged on the can that either shoulder will engage the rim of the cover to raise the same, when the projecting finger-piece of said device is 25 turned.
2. The combination of a box body, a removable cover, a recess located on the outside of the body below the upper edge thereof and on that part of the body, lapped by the cover when in position, and an opener having a part 30 pivoted in said recess and a part extending at an angle to such first part and resting under the lower edge of the flange of the cover, so that by rotating the opener on its pivot the angle part of the opener engages the edge of the cover flange and forces the cover off the box.
3. The combination of a body, a removable cover, and an opener, such opener comprising a member extending between the cover and the body and pivotally attached to the exterior of such body, and a member extending at an 35 angle to the first named member just under the edge of the cover and arranged to be turned and thereby to force the edges of such opener, which are underneath the lower edges of the cover, around the pivotal point of attachment, thus raising the cover from the body without disturbing the contents thereof, substantially as described.
4. The combination of a box body, a removable cover, a recess, formed on the outside of the body in the part lapped by the cover, an aperture in the recess, and an opening 40 device pivoted in said recess by means of a spur integral with such opener and which passes through such aperture and is headed down on the inside of the body, said opener having an outwardly extending portion adapted to engage under the edge of the flange of the cover when the cover is 50 in closed position.
5. The combination of a can body, a cover, and an opening device pivotally attached to the body, below the top edge of same, and between the cover and the body when the cover is in place, and provided with a finger-piece extending at right-angles to the lever-arm, and di-

rectly under the edge or rim of the cover, so that, upon turning about its pivot, the opening device will raise 60 the cover by bearing against the edge or rim of the cover.

6. In combination with a box and cover fitting thereon, one member thereof being provided with an opening in the portion adapted to be over-lapped by the other member, of means for prying off the cover having a pivot adapted to enter said opening.

7. In combination with a box and cover fitting thereon, one member thereof being provided with an opening in the portion adapted to be over-lapped by the other member, of means for prying off the cover having a pivot formed integral therewith and adapted to enter said opening and engage the member.

8. In combination with a box and cover fitting thereon, of an opener pivotally connected to one member thereof and consisting of a portion lying between the box and 75 cover and a handle portion projecting outwardly from below the junction of the box and cover and adapted when turned to engage one member of the box and cover and force the cover from engagement with the box.

9. In combination with a box and a cover fitting thereon, of a device pivotally supported between the over-lapping parts of the box and cover, and adapted when turned to disengage the cover from the box.

10. The combination with a box and cover fitting thereon, of a device pivotally connected with a portion of the 85 box which is over-lapped by the cover and adapted when turned to disengage the cover from the box.

11. In combination with a box and cover fitting thereon, said box having a circumferential head near the upper edge thereof, of a device, pivotally secured at the mouth 90 of the box and adapted to have a portion thereof covered by the cover and a portion lie normally between the lower edge of the cover and the head, the portion covered by the cover being compressed between the box and the cover, and means for turning the device so that the portion between the head and the lower edge of the cover will engage the same and force the cover upwardly, the compressed portion holding the cover from engagement with the box and assisting the upward movement of the cover.

12. In combination with a box and cover fitting thereon, 100 the box having a circumferential head near the mouth thereof, of an opening device consisting of a handle, and a right-angled projection formed integral therewith pivotally connected to the mouth of the box above the head and having its angle resting between the lower edge of the 105 cover and bead, for the purpose set forth.

13. In combination with a box and cover fitting thereon, the box having a circumferential head near the mouth thereof and having an opening above the head, of an opening device consisting of a handle and a right-angled portion formed integral therewith, the right-angled portion having a centrally-arranged bent terminal entering the opening of the box to form a pivot for the opener, and the angle resting between the head and the lower edge of the cover, for the purpose set forth.

ROBERT S. HILTNER.
